Patented May 14, 1912.

UNITED STATES PATENT OFFICE.

WILLIAM MARSHALL AND NEWTON SIMISON, OF DES MOINES, IOWA.

ANCHOR.

1,026,402.

Specification of Letters Patent. Patented May 14, 1912.

Application filed April 27, 1911. Serial No. 623,651.

To all whom it may concern:

Be it known that we, WILLIAM MARSHALL and NEWTON SIMISON, citizens of the United States, residing at Des Moines, in the county 5 of Polk and State of Iowa, have invented a certain new and useful Anchor, of which the following is a specification.

The object of our invention is to provide an anchor for telegraph poles and the like 10 of simple, durable and inexpensive construction which can be easily and firmly fixed in the ground, and which has parts which can be driven into the ground at right angles to a guy wire or the like secured to said anchor 15 without disturbing the ground into which said parts are driven.

More particularly it is our object to provide an anchor of such a kind having parts which may be readily and easily driven into 20 the solid earth at the bottom of the hole at right angles to such a guy wire.

Another object of our invention is to provide means whereby such parts at the bottom of a hole may be easily and readily 25 driven into the earth, said means being operated from the surface of the earth.

A further object of our device is to provide such an anchor which may be easily and readily taken apart and placed in a 30 small space for storage or transportation, and all parts of which except the base plate, anchor plates and anchor rod may be removed after the anchor is set, and used again.

Our invention consists in certain details 35 in the construction, arrangement and combination of the various parts of the device, whereby the objects contemplated are attained, as hereinafter more fully set forth, 40 pointed out in our claims and illustrated in the accompanying drawings, in which—

Figure 1 shows a side elevation of an anchor embodying our invention. Fig. 2 shows a top or plan view of the base plate of the 45 anchor with the movable anchor plates inserted therein. Fig. 3 shows a transverse central sectional view of the same with the anchor rod in place. Fig. 4 shows a plan view of one of the anchor plates. Fig. 5 shows a perspective view of the slotted wedge block, and Fig. 6 shows a perspective 50 view of the tamping or driving device.

Our improved anchor is preferably constructed wholly of metal.

In the accompanying drawings, we have 55 used the reference numeral 10 to indicate a base plate which is shown in the drawing

to be cylindrical in shape but which may be made in other forms. The base plate 10 is 60 constructed with the central opening 11 designed to receive the anchor rod 12 which is provided with a head 13 at its lower end by which the rod is held in the base plate. The anchor rod 12 is constructed with a loop 12^a at its upper end. The base plate is 65 constructed with slots 14 on opposite sides of the opening 11, which slots extend from points spaced apart from the opening 11 to the outer edge of the base plate and are designed to receive the wedge block hereinafter described. The base block 10 is also 70 constructed with a slot 16 extending through said block horizontally in the same direction as the slots 14, designed to receive the anchor plates 15 hereinafter described. The 75 base plate is solid for a short distance around the opening 11. The base plate 10 is provided with flanges 17 and 18 around its outer circumference adjacent to the slot 16, said flanges extending approximately 80 half way across the slot 16 and being located on the upper side of the slot 16 on one side of the base plate and on the lower side of said slot on the other of said base plate, as shown in Fig. 3.

Slidably received in the slot 16 on the 85 respective sides of the base plate 10 are anchor plates 15, the thickness of which is substantially half the width of the slot 16. The plates 15 are substantially rectangular in shape and somewhat shorter than the diameter of the base plate 10. The outer ends of the plates 15 are constructed in the form of a circle with its center at the center of the base plate 10 and with a diameter 90 slightly less than the length of the base plate 10, in order that the anchor plates 15 may be wholly received in the slot 16 with their ends resting against the flanges 17 and 18. The anchor plates 15 are provided 100 with longitudinal slots 18^a designed to slidably receive the solid central portion of the base plate 10, the portion of said anchor plates adjacent to the inner end of the slot being preferably curved as shown in Fig. 4. 105 The anchor plates 15 are slidably received on each side of the base plate 10 within the slot 16 and when inserted therein rest substantially one above the other as shown in Fig. 3. For driving the anchor plates 15 from their position within the base plate 10, we provide a wedge block 19 which is substantially triangular in cross section and is 110 constructed with a slot 20 extending from

its apex to a point spaced apart from its base, the said slot being designed to slid-
5 ingly receive the solid central portion of the
base block, the apex of the wedge block thus
being forked. We preferably construct the
wedge block 19 with a projection 21 cen-
trally located on its base, said projection be-
ing substantially cylindrical in cross section,
which projection receives the force of the
10 blow when the wedge is being driven. Near
the upper end of the projection 21, we pro-
vide laterally extending lugs 21^b for a pur-
pose hereinafter explained. The base of the
wedge block 19 and the projection 21 are
15 provided with a central slot 21^a, elongated
in a direction at right angles to the base of
the wedge block 19, and extending from the
outer end of the projection 21 to the slot 20.
The edges of the base block from the apex
20 of the base are preferably rounded, as shown
in Fig. 5, or may be rounded except near
the base as shown in Fig. 1. The wedge
block 19 is mounted on the anchor rod 12
25 with its apex received in the slots 14 and is
designed to be driven downwardly to spread
apart the anchor plates 15.

We provide a tamping or driving device
comprising an arm or handle 22, a base
or driving portion 23, and a portion 24 at
30 the upper end of the handle for engaging
the wedge block and withdrawing it from
the hole in which the anchor is placed. The
base portion 23 is constructed with a longi-
35 tudinal slot 25 substantially parallel with
the arm 22, which arm 22 is secured to the
upper end of the base portion 23 at the side
of the slot 25. The slot 25 is of proper size
to slidably receive the anchor rod 12. At
40 the upper end of the handle 23 is a portion
24 constructed with a slot similar to the
slot 25 designed to slidably receive the
anchor rod 12. The end of the portion 24
is constructed with a cylindrical opening
45 shown in Fig. 1, designed to receive the pro-
jection 21. Formed in the side of the por-
tion 24 are slots 26 which with the lugs 21^b
50 form bayonet joints when the projection 21
is received in the opening in the portion 24.
The inner end of the slot 26 is laterally elon-
55 gated in the direction of the longitudinal
axis of the handle 22. The portion 24 is
designed to withdraw the wedge block 19
from the hole in which the anchor is planted.
The projection 21 is received in the cylin-
60 drical opening in the portion 24 and the lugs
21^b are received in the slots 26 when it is
desired to withdraw the wedge.

In assembling and planting our anchor,
we insert the anchor rod 12 in the opening
65 11 and form the loop 12^a. We then insert
the anchor plates 15 in the slot 16 on the
opposite sides of the base plate 10. We then
mount the wedge block 19 on the anchor rod
12 with its forked end received in the slots
65 14. The tamping device is then mounted on

the anchor rod 12 with the said rod received
in the slot 25. The anchor is then placed at
the bottom of a hole and the anchor plates
15 may be forced apart by driving the
wedge block 19 downwardly with the tam-
70 ping device. After the anchor plates 15 are
driven into the ground at the sides of the
hole the tamping device is removed and the
withdrawing device is placed over the an-
chor rod 12 with said rod received in the
slot provided therefor. The projection 21
is received in the cylindrical opening in the
portion 24 and the lugs 21^b are received in
the slots 26. The handle 22 is given a slight
80 rotary motion, and the portion 24 is there-
by locked in position by means of the bayo-
net joints formed by the lugs 21^b and the
slots 26. The purpose of the extension at
the inner end of the slot 26 hereinbefore de-
scribed is now clear. By means of said ex-
tension, a certain play or longitudinal move-
ment of the portion 24 on the extension or
projection 21 is permitted and thereby a
jerking movement may be employed in
withdrawing the wedge block 19. When the
wedge block 19 and the clamping device are
90 removed from the hole, the latter may be
filled and a guy wire secured to the loop 12^a
at the upper end of the anchor rod 12.

The special advantage of our device lies
95 in its means for driving the anchor plates
into the solid ground from a position above
the surface of the ground, thus leaving the
anchor firmly embedded in the ground
which has not been disturbed by recent dig-
ging, and also in the construction and ar-
rangement of the parts of our device, which
enables the user to withdraw from the hole
100 in the ground all the parts except those
necessary for a permanent anchor, and
which makes it possible to use the other
parts again.

The advantages of the wedge block over
ordinary means for forcing the anchor
plates or similar devices into the solid
110 ground at the side of the hole are consider-
able. The power from the wedge block is
applied directly to the inner ends of the
anchor plates and a blow on the upper end
of the wedge block is directly imparted to
115 the anchor plates.

We claim as our invention:

1. In a device of the class described, a base plate designed to be placed at the bottom of a hole of slightly larger diameter than said plate, anchor plates slidably received in said base plate, a V shaped wedge, the apex of which is slidably received in the said base plate at right angles to the surface thereof and engaging the inner edges of said anchor plates.
2. In a device of the class described, a base plate designed to be placed at the bottom of a hole of slightly larger diameter than said plate, anchor plates slidably re- 125

ceived in said base plate, a V shaped wedge, the apex of which is slidingly received in the said base plate at right angles to the surface thereof and engaging the inner 5 edges of said anchor plates, means for driving said wedge downwardly and thus forcing said anchor plates laterally into the ground.

3. In a device of the class described, a 10 base plate designed to rest in the bottom of a hole, said plate being constructed with a central opening with a solid central portion around said opening and with slots on opposite sides of said opening designed to receive the points of a slotted V shaped wedge, a V shaped wedge slotted from its apex to a point spaced apart from its base, the apex of said wedge being slidingly received in the slots in said base plate with 15 the solid central portion of said base plate received in the slot in said wedge, anchor plates slidingly received in said base plate, each of said anchor plates being slotted on its side adjacent to said wedge to slidingly receive the same, when said anchor plates are received in the base plate.

4. In a device of the class described, a base plate designed to rest in the bottom of a hole, said plate being constructed with a 20 central opening, and with a solid central portion around said opening and with slots on opposite sides of said opening designed to receive the points of a slotted V shaped wedge, a V shaped wedge slotted from its apex to a point spaced apart from its base, and constructed with a central opening in its base extending to said slot, the apex of said wedge being slidingly received in the slots in said base plate with the solid central 25 portion of said base plate received in the slot in said wedge, anchor plates slidingly received in said base plate, each of said anchor plates being slotted on its side adjacent to said wedge to slidingly receive the same, means for driving said wedge downwardly to spread said anchor plates apart.

5. In a device of the class described, a base plate designed to rest in the bottom of a hole, said plate being constructed with a 30 central opening, and with a solid central portion around said opening and with slots on opposite sides of said opening designed to receive the points of a slotted V shaped wedge, a V shaped wedge slotted from its apex to a point spaced apart from its base, and constructed with a central opening in its base extending to said slot, the apex of said wedge being slidingly received in the slots in said base plate with the solid central 35 portion of said base plate received in the slot in said wedge, anchor plates slidingly received in said base plate, each of said anchor plates being slotted on its side adjacent to said wedge to slidingly receive the same, means for driving said wedge downwardly to spread said anchor plates apart.

6. In a device of the class described, a base plate designed to rest in the bottom of a hole, said plate being constructed with a 40 central opening, and with a solid central portion around said opening and with slots on opposite sides of said opening designed to receive the points of a slotted V shaped wedge, a V shaped wedge slotted from its apex to a point spaced apart from its base, and constructed with a central opening in its base extending to said slot, the apex of said wedge being slidingly received in the slots in said base plate with the solid central 45 portion of said base plate received in the slot in said wedge, anchor plates slidingly received in said base plate, each of said anchor plates being slotted on its side adjacent to said wedge to slidingly receive the same, means for driving said wedge downwardly to spread said anchor plates apart.

adjacent to said wedge to slidingly receive the same, means for driving said wedge 65 downwardly to spread said anchor plates apart, and means for withdrawing said wedge block from said base plate after said anchor plates have been driven into the ground.

7. In a device of the class described, a base plate designed to rest in a hole in the ground, constructed with a central opening with a solid portion around said opening and with slots extending from said solid portion in opposite directions to the outer edge of the said base plate, a V shaped wedge slotted from its apex to a point spaced apart from its base, and constructed with a central opening in its base extending to said slot, the apex of said wedge being slidingly received in the slots in said base plate with the solid central portion of said base plate received in the slot in said wedge, anchor plates slidingly received in said base plate, each of said anchor plates being slotted on its side adjacent to said wedge to slidingly receive the same, and an anchor rod received in the central opening in said base plate and in the opening in the base of said V shaped 90 wedge.

8. In a device of the class described, a base plate designed to rest in a hole in the ground, constructed with a central opening with a solid portion around said opening 95 and with slots extending from said solid portion in opposite directions to the outer edge of the said base plate, a V shaped wedge slotted from its apex to a point spaced apart from its base, and constructed with a central opening in its base extending to said slot, the apex of said wedge being slidingly received in the slots in said base plate with the solid central portion of said base plate received in the slot in said wedge, anchor plates slidingly received in said base plate, each of said anchor plates being slotted on its side adjacent to said wedge to slidingly receive the same, and an anchor rod received in the central opening in said base plate and in the opening in the base of said V shaped wedge, means for driving said wedge downwardly, means for withdrawing said wedge.

Des Moines, Iowa, April 19, 1911.
